UNITED STATES PATENT OFFICE.

JACOB DINCKELS, OF MAINZ, GERMANY.

EVAPORATOR.

984,265.

Specification of Letters Patent. Patented Feb. 14, 1911.

Application filed August 26, 1910. Serial No. 579,021.

To all whom it may concern:

Be it known that I, JACOB DINCKELS, a subject of the Grand Duke of Hesse-Darmstadt, and resident of Mainz, in the Grand 5 Duchy of Hesse-Darmstadt, German Empire, have invented certain new and useful Improvements in Evaporators, of which the following is a specification.

This invention relates to evaporators of 10 the circulating type. Such evaporators as at present constructed have the defect that during rapid boiling a great deal of bubbling and frothing takes place, in consequence of which liquid in minute qualities may easily 15 be carried over. Under these conditions it is also not possible to utilize the apparatus to its full evaporating capacity since in order to avoid too much frothing it is often necessary to reduce the evaporating capacity by 20 reducing the admission of steam used for heating. Obviously the control also of the boiling process is seriously affected by the aforesaid defects.

The object of the present invention is to 25 avoid these defects as far as possible.

In the accompanying drawings Figure 1 is an elevation partly in section of one form of the improved evaporator according to 30 the present invention showing an inclined evaporating pan and the heating apparatus arranged outside the pan. Fig. 1^a is a cross section through the heating apparatus on the line C—D of Fig. 1. Fig. 2 is a similar view showing a modification with a vertical 35 pan, Fig. 3 is a vertical section showing a modified construction with vertical pan and internal heating device. Fig. 4 is a horizontal section on the line A—B of Fig. 3, and Figs. 5 and 6 are views similar to Fig. 40 3 showing further modifications.

Referring to Fig. 1 an inclined evaporating pan is shown at *d* provided with outlet *b* for the vapor. Below the mouth of the branch *f* of the up-take pipe *c* is arranged 45 a horizontal plate *a* above the level of the fluid in the pan. The heating apparatus is shown outside the evaporating pan *d* and consists of a cylindrical body *g*, see also Fig. 1^a, which is provided with two end 50 chambers by transverse tube plates *h* and *i* connected by tubes *m* secured in the plates. The space between the two plates *h* and *i* is divided by a baffle plate *n* extending to the right as far as the plate *i* but leaving a

space to the left between the end of the baffle 55 plate and the plate *h*. An inlet for the steam or other heating medium is shown at *o* and an outlet at *p*, so that the steam entering at *o* flows between the tubes *m* toward the left and passing between the baffle plate 60 and tube plate *h* returns to the right and escapes at *p*. The chamber *l* is shown divided by a horizontal wall *l'* the down-take pipe *q* from the pan *d* being connected below and the uptake pipe *c* above the wall 65 *l'* so that the liquid as it drops from the pan *d* is compelled to flow through one half of the tubes *m* to the left into the chamber *l* returning to the right through the other half of the tubes to the compartment above 70 the wall *l'* and rising through the uptake pipe *c*. Of course the heating apparatus can also be arranged vertically.

The liquid to be treated before heating is at first at the same level in the pipe *c* 75 and pan *d*. When the heating medium is admitted into the heating apparatus steam bubbles are formed in the liquid and circulation is initiated so that finally a continuous stream flows out through branch *f* and 80 falls upon the plate *a* over which it flows in a thin film from which the steam has no difficulty in escaping so that no frothing can take place thus avoiding any carrying over of small globules of liquid. The vapor 85 escapes through the outlet *b*. The outflow of the vapor may be facilitated by exhausting and the maintenance of a vacuum.

The arrangement shown in Fig. 2 as applied to a vertically arranged pan is practically the same as that described with reference to Fig. 1 the corresponding parts being indicated by like letters of reference. The plate *a* however is shown slightly inclined 90 so as to increase the rate of flow of the liquid 95 over the plate.

In Figs. 3-6 the heating apparatus is arranged within the body of liquid in the pan, so that a plurality of circulating jets is obtained. In these figures the heating tubes 100 *m* are shown arranged as an annular series connecting the chamber *l* formed between the bottom of the pan and the tube plate *i* with the chamber formed between the tube plate *h* and a division plate *s*. The heating 105 chamber *g* is closed by the tube plates *h* and *i* the outer shell of the pan and an inner central tube *r*. The level of liquid is above

the plate *s* and a central down-take pipe *q* is provided passing through the tube *r* and extending from the plate *s* to below the tube plate *i*. The tube *q* is of such a diameter as 5 to provide a clearance space between the two tubes *q* and *r* so as to utilize the tube *r* as a heating surface. In Fig. 3 two curved jet pipes *f* are shown in connection with the chamber between the tube plate *h* and plate 10 *s*. As already described with reference to Fig. 1 the heating medium entering at *o* passes between the tubes *m* and escapes at *p*. No baffle plates are here shown but the course of the heating medium may be also 15 controlled as desired. As the liquid in the tubes *m* and the portion adjacent to the surface of the tube *r* becomes heated the steam bubbles rise and the colder liquid drops through pipe *q*, until a continuous stream 20 flows out of pipes *f* upon the plate *a* over which the liquid flows in a thin film, and drops back over the edge or edges of the plate into the body of liquid in the pan, so that the vapor readily escapes. In Fig. 5 25 the body of the evaporating pan *d* is relatively larger than the lower heating portion and the uptake pipes *f* extend vertically and project through the plate *a*. The pipes *f* are provided with diverting caps *t*, the liquid overflowing between the top of the pipes 30 and the caps, or the top of the pipes *f* below the cap may be perforated as shown at *u*. A plurality of film plates may also be employed. For instance in Fig. 6 two such 35 plates are provided. Above the plate *a* is arranged a second plate *a'* extending nearly across the full width of the pan and provided with a central opening *a*². In the construction shown the pipes *f* extend to the 40 level of the upper plate *a'* only so that as the liquid rises it flows over the plate *a'*, falls in a cascade over the edges of the opening *a*² upon the plate *a* over which it flows and drops finally into the body of the liquid. 45 The vapor rising from the plate *a* can escape between the plate *a'* and the shell of the pan *d* as well as through the opening *a*². It will be understood that the number of jet pipes *f* may be increased if desired, and also that the 50 uptake passages shown in Figs. 3, 5 and 6 may be replaced by an annular passage of corresponding cross-section area. The evaporating device according to the present invention may be employed for distilling processes.

I claim:—

1. The combination with an evaporating apparatus having a heating chamber for the liquid to be treated, means for heating said 60 chamber, an evaporating chamber and a down-pipe connecting said evaporating chamber with the colder part of said heating chamber; of a plate arranged above the level of the liquid in said evaporating chamber

and an up-take pipe extending from the hotter part of said heating chamber and opening above said plate, the liquid from said up-take pipe spreading over said plate in a thin film and from thence falling into the liquid in said evaporating chamber. 65 70

2. The combination with an evaporating apparatus having a heating chamber for the liquid to be treated, means for heating said chamber, an evaporating chamber and a down-pipe connecting said evaporating chamber with the colder part of said heating chamber; of a plurality of plates arranged above the level of the liquid in said evaporating chamber and an up-take pipe extending from the hotter part of said heating chamber and opening above said plates, the liquid from said up-take pipe spreading in a thin film over first one plate and then another before falling into the liquid in said evaporating chamber. 75 80 85

3. The combination with an evaporating apparatus having a heating chamber for the liquid to be treated, means for heating said chamber, an evaporating chamber and a down-pipe connecting said evaporating chamber with the colder part of said heating chamber; of a substantially horizontal plate arranged above the level of the liquid in said evaporating chamber and an up-take pipe extending from the hotter part of said heating chamber and opening above said plate, the liquid from said up-take pipe spreading over said plate in a thin film and from thence falling into the liquid in said evaporating chamber. 90 95 100

4. An evaporating apparatus comprising in combination, a heating chamber for the liquid to be treated, said chamber comprising end compartments and intermediate connections, means for heating said chamber, an evaporating chamber separate from said heating chamber, a down-pipe connecting the lower part of said evaporating chamber with the colder compartment of said heating chamber, an up-take pipe extending from the hotter compartment of said heating chamber and opening into said evaporating chamber above the level of the liquid therein, and a plate intermediate the level of the liquid and the mouth of said up-take pipe, the liquid from said up-take pipe spreading over said plate in a thin film and from thence falling into the liquid in said evaporating chamber. 105 110 115

5. An evaporating apparatus comprising in combination, a heating chamber for the liquid to be treated, said chamber comprising end compartments and intermediate connections, means for heating said chamber, an evaporating chamber separate from said heating chamber, a down-pipe connecting the lower part of said evaporating chamber with the colder compartment of said heat- 120 125

ing chamber, an up-take pipe extending from the hotter compartment of said heating chamber and opening into said evaporating chamber above the level of the liquid 5 therein, and a substantially horizontal plate intermediate the level of the liquid and the mouth of said up-take pipe, the liquid from said up-take pipe spreading over said plate

in a thin film and from thence falling into the liquid in said evaporating chamber.

In witness whereof I have hereunto set my hand in the presence of two witnesses.

JACOB DINCKELS.
